TRAY

Julius P. Katz, Brooklyn, N. Y.

Application April 15, 1952, Serial No. 19,330

Term of patent 7 years

(Cl. D44—10)

To all whom it may concern:

Be it known that I, Julius P. Katz, a citizen of the United States, residing at Brooklyn, in the county of Kings and State of New York, have invented a new, original, and ornamental Design for a Tray, of which the following is a specification, reference being had to the accompanying drawing, forming a part hereof.

Fig. 1 is a top perspective view of a tray, showing my new design;

Fig. 2 is a side elevational view; and

Fig. 3 is an end elevational view thereof.

I claim:

The ornamental design for a tray, as shown.

JULIUS P. KATZ.
